(57) **CLAIM**

We claim the ornamental design for a display board, as shown and described.

DESCRIPTION

FIG. 1 is a front perspective view of a display board, according to one embodiment;

FIG. 2 is a rear view of a display board of FIG. 1;

FIG. 3 is a left side view of a display board of FIG. 1, the right side view is a mirror image of the left side view of FIG. 3;

FIG. 4 is a bottom view of a display board of FIG. 1;

FIG. 5 is a front perspective view of a display board, according to another embodiment;

FIG. 6 is a rear view of a display board of FIG. 5;

FIG. 7 is a left side view of a display board of FIG. 5, the right side view is a mirror image of the left side view of FIG. 7; and,

FIG. 8 is a bottom view of a display board of FIG. 5.

The broken lines in FIGS. 5 and 6 are shown for the purpose of illustrating environmental structure and form no part of the claimed design.
